Primary Examiner — Lilyana Bekic*Assistant Examiner* — Lee D. Starr(74) *Attorney, Agent, or Firm* — Saidman DesignLaw Group, LLC(57) **CLAIM**

The ornamental design for a pad for nerve stimulator device, as shown and described.

DESCRIPTION

FIG. 1 is a perspective view of a pad for nerve stimulator device showing our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.
